US0D1054751S

(12) **United States Design Patent** (10) **Patent No.:** **US D1,054,751 S**
(45) **Date of Patent:** **** Dec. 24, 2024**

(54) **LIFTING DESK**

(71) Applicant: **Hangzhou Hengjian Supply Chain Technology Co., Ltd.**, Hangzhou (CN)

(72) Inventor: **Pengjun Ye**, Hangzhou (CN)

(73) Assignee: **Hangzhou Hengjian Supply Chain Technology Co., Ltd.**, Hangzhou (CN)

(**) Term: **15 Years**

(21) Appl. No.: **29/888,411**

(22) Filed: **Mar. 30, 2023**

(30) **Foreign Application Priority Data**

Feb. 27, 2023 (CN) 202330075609.5

(51) **LOC (14) Cl.** **06-03**

(52) **U.S. Cl.**

USPC **D6/654.14**

(58) **Field of Classification Search**

USPC D6/329, 641, 653, 653.1, 653.14, 653.15, D6/653.21, 653.22, 654, 654.1, 654.14, D6/654.15, 654.21, 654.22, 656, 656.16, D6/656.17, 656.18, 657, 685, 691, 691.5, D6/691.9

CPC ... A47B 9/20; A47B 21/02; A47B 2200/0056; A47B 2200/0062

(57) **CLAIM**

The ornamental design for a lifting desk, as shown and described.

DESCRIPTION

FIG. 1 is a perspective view of my new design, showing a lifting desk;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged partial view of an area labeled 9 in FIG. 1;

FIG. 10 is an enlarged partial view of an area labeled 10 in FIG. 2; and,

FIG. 11 is an enlarged partial view of an area labeled 11 in FIG. 2.

The dash-dot-dash lines encircling claimed subject matter depict the cut lines of the enlarged views and form no part of the claim.

The dashed broken lines depict portions of the lifting desk that form no part of the claimed design.

1 Claim, 11 Drawing Sheets
